INVENTOR

J. L. Dibble

UNITED STATES PATENT OFFICE.

JOHN L. DIBBLE, OF BROOKLYN, NEW YORK.

PUZZLE.

SPECIFICATION forming part of Letters Patent No. 340,296, dated April 20, 1886.

Application filed May 13, 1885. Serial No. 165,289. (No model.)

To all whom it may concern:

Be it known that I, JNO. L. DIBBLE, a citizen of the United States, residing at Brooklyn, in the county of Kings and State of New York, have invented a new and useful Puzzle, of which the following is a specification.

My invention relates to that class of puzzles which consist of a series of pieces susceptible of being arranged in contact, and to thus form a symmetrical figure; and it consists in forming from suitable material a series of pieces each in the form of a rectangular parallelogram, the series being susceptible of being arranged in contact in the form of a square, the pieces being of varying dimensions and so proportioned as to furnish no index of the relative positions in which they should be placed to attain the end.

The following is what I consider the best means of carrying out the invention, reference being had to the accompanying drawings, which form a part of this specification, and in which—

Figure 1 shows the puzzle in a complete form. Fig. 2, which is drawn to the same scale as Fig. 1, shows the several pieces comprising the square, together with an additional piece, the uses of which will be hereinafter explained, all arranged in the order of their respective sizes. Figs. 3 and 4 show modified plans upon which the dimensions and proportions of the parts of the device may be based.

Any material susceptible of being worked into and having sufficient rigidity to retain the described forms may be used. Sheet metal, pasteboard, thin wood, &c., are suitable. The size of the square having been chosen, it is to be divided into a series of rectangular parallelograms. This I call the "primary division." Part or all of the resulting pieces are to be again divided in such manner that the resulting parts will each be in the form of a rectangular parallelogram, and that all of the parts may be as nearly as is practicable of uniformly varying sizes. This I call the "sub-division."

In Fig. 1 the plain dividing-lines indicate the primary division, and the short lines, bordered by rows of dots, indicate the subdivision. In Figs. 3 and 4 the primary division only is shown.

The method of making the primary division

may be greatly varied; but it is important that the resulting parts be of varying dimensions, that the greater number of the parts be other than aliquot parts of the square, and that the differing dimensions shall not be a geometrical progression. I deem it best that this primary division be made in such a manner that the resulting parts shall be of equal widths and of varying lengths.

Referring to the drawings, it will be seen that in Fig. 1 the primary division results in seven parts of equal width, three of which are three times as long as wide, and four of which are four times as long as wide; that the division in Fig. 3 results in six parts of equal width, two of which are twice as long as wide, and four of which are three times as long as wide; that the division in Fig. 4 results in seven parts of equal width, two of which are five times as long as wide, two of which are four times as long as wide, two of which are three times as long as wide, and one of which is square. It will be observed that in each case the division results in a series of parts of equal width. While this feature is not essential and may be departed from, I deem it desirable, as it facilitates the subdivision of the parts into a uniformly-graduated series.

It is desirable that the primary division be such that its plan may not be easily discovered; but it should be borne in mind that the subdivision will increase the number of parts and correspondingly decrease their dimensions. Care should therefore be used that these effects may be kept within suitable limits.

In making the subdivision the aim should be to produce a series of parts, each in the form of a rectangular parallelogram, the whole being as nearly as possible of uniformly-graduated sizes, the dimensions of the parts increasing by equal increments and not in geometrical progression. The practicability of doing this will be governed by the plan adopted in making the primary division. The difference between any one part and another should be sufficient to be apparent, and in some cases it will prove impracticable to produce a single series of uniform graduation without making the difference between the parts too slight. In such cases the parts may be separated in two or more groups, each of which may be separately subdivided, so that

its resulting parts may be of uniform graduation. In other cases the difficulty may be obviated by omitting to subdivide one or more of the parts resulting from the primary division, and so subdividing the remainder that these parts may, without change, serve to complete the graduation of the whole. The part *i* in Fig. 3 and the parts *k* and *l* in Fig. 4 are instances in which this course may be followed to advantage.

Fig. 1 shows the square divided in fourteen parts. It is evident that if the sum of the superficial areas of the several parts be computed that the square root of this sum will equal the length of one side of the square. That this fact may not be used as an aid to the solution of the puzzle, and to further increase the difficulty of such solution, I introduce a supernumerary piece of similar form and make it a part of the graduated series. (See *h* in Fig. 2.) It being stated as a condition of the solution that one piece of the series is to be discarded, it will be impossible to form and perfect the square unless the right piece is first discovered and discarded, which in practice it will be found very difficult to do. While I deem the introduction of such supernumerary piece a valuable feature of my invention, it may be omitted. The puzzle as otherwise described is substantially complete in itself and difficult of solution. It should be determined whether or not the supernumerary piece is to be used before making the subdivision, that the graduation of the parts may be made accordingly. When the subdivision is made in two or more series, the supernumerary piece may be incorporated in either of them.

In making the primary and subdivisions it is not necessary that a square be actually made and divided. The dimensions of the square and the plan of the primary division being decided upon, any competent draftsman will be able to lay it out on paper, and from it make the subdivision and compute the exact dimensions of each of the resulting parts.

Each of the parts may be made to dimensions separately from the others, and the whole afterward be properly assembled. When they are made of sheet material, the rectangular form of the pieces facilitates the cutting, permits such cutting to be done with the usual appliances for the purpose, and contributes to the economical use of the material.

An important feature of the puzzle is its usefulness for advertising purposes, especially of wares for domestic or personal use. For such purposes the puzzle may be made of cardboard or similar material, and suitable designs or inscriptions be printed on a part or all of the pieces, thus producing a series of business

cards, which, by reason of their interest and value as a puzzle, will probably be preserved intact and be frequently exposed in home and social circles. The rectangular form of the pieces makes them most suitable to receive advertising inscriptions and designs, and also greatly facilitates the operations of printing and cutting, whether the pieces are first cut and afterward separately printed, or are printed in sheets and afterward cut and assembled.

Other than the described modifications may be made without departing from the principle of the invention—as, for instance, the subdivision may be so made as to result either in a series of parts of graduated width and of uniform length, or in a series in which both length and width are graduated.

It is to be understood that in the solution of the puzzle the parts are to be placed in close contact, edge to edge, without open spaces between them, and that the superficial area of the square so formed shall be equal to the aggregate superficial area of all of the parts, except in cases where the supernumerary piece, as described, is introduced. In such cases the superficial area of the square shall be equal to the aggregate superficial area of all of the parts, except the supernumerary piece.

I am aware that a patent was granted to one Scott, dated April 3, 1883, No. 274,980, for an improvement in toy building-blocks, the said blocks being each a portion of a cube, and the size of the cube being a multiple or a factor of other cubes formed of similar larger or smaller blocks. I therefore do not claim such a device or combination; but

What I do claim as my invention, and desire to secure by Letters Patent, is—

1. A puzzle consisting of one or more series of rectangular pieces susceptible of being arranged in contact, edge to edge, in the form of a square of given dimensions, the pieces in each series being of graduated dimensions and not all of them aliquot parts of any other piece or of the whole square, substantially as set forth.

2. In combination with a puzzle composed of a series of pieces of varying dimensions, each piece being in the form of a rectangular parallelogram, and the whole of the pieces susceptible of being arranged in contact in the form of a square having a superficial area equal to the aggregate superficial area of the pieces, an additional piece of similar form and of approximate dimensions, substantially as and for the purposes set forth.

JNO. L. DIBBLE.
